PNEUMATICALLY-OPERATED SLEEVE VALVE

Richard H. Wolfe, Maywood, N.J., assignor to Bendix Aviation Corporation, Teterboro, N.J., a corporation of Delaware

Application October 1, 1954, Serial No. 459,788

1 Claim. (Cl. 251—63)

This invention relates to new and useful improvements in air driven turbines, and it is particularly concerned with a system having as its general object the operation of the turbine at a constant speed rate.

A further object of the invention is to provide an air driven turbine system which will not only operate at a constant speed rate but which will continue that speed rate without appreciable time lag, as it is constantly loaded and unloaded.

The foregoing objects as well as others are accomplished by novel and improved governing means that is quickly responsive to variations in the speed of the turbine and is operable to quickly effect an increase or decrease in the turbine speed as may be required to hold the turbine to a constant rate.

A feature of the invention lies in the nature of the control means. This includes an air supply control valve connected to the turbine and a governor device operated by the turbine to vary the supply of air through the valve to the turbine accordingly as the speed of the governor increases or decreases.

The governing means is characterized by its quick response to increase the supply of air to the turbine when the latter is being loaded and to do so with a minimum of time lag whereby the constant speed rate of the turbine is continued. The response is also prompt in decreasing the pressure air supply to the turbine when the latter is unloaded. This feature of the invention makes it particularly useful as a means for powering an actuator surface control system where constant loading and unloading of the power drive takes place, such as in the case of its use with an aileron actuator unit.

The foregoing and other objects and advantages of the invention will appear more fully hereinafter from a consideration of the detailed description which follows, taken together with the accompanying drawings, wherein an embodiment of the invention is illustrated. It is to be expressly understood, however, that the drawings are for purposes of illustration and description and are not to be construed as defining the limits of the invention.

Figs. 1 and 1A comprise a view of the governed air driven turbine power drive system embodying the invention, some parts being sectioned to better illustrate the invention; and

Fig. 2 is a right-end view of the governor device.

In describing the invention in further detail, reference is now directed to the drawings wherein there is disclosed an air driven turbine 1, a valve member 2 that communicates pressure air from a supply source, not shown, to drive the turbine, and a governor 3 responsive to the speed of the turbine and operable to control the valve member to increase or decrease pressure air flow to the turbine as required.

The turbine illustrated is of the radial impulse type, supported on a drive shaft 4 in a volute housing 5. The housing is formed to guide pressure air received through an intake end 6 to a plurality of nozzles 7. The pressure air flows through the nozzles and radially attacks

the blades of the turbine, whereupon the latter rotates the drive shaft 4 on which it is mounted. The used pressure air exits axially through an exhaust 8. The pressure air supply is provided by a suitable source, which may be bleed air from the compressor unit of an associated aircraft.

The valve member 2, through which pressure air is fed to the turbine, is embodied in an elongated housing 9 (Fig. 1A). The latter has an inlet 11 into one end. 10 This inlet passage extends interiorly into the housing and at its inner portion encircles a cylindrical skirt wall 12 of the housing, which wall extends laterally into the inlet passage. The skirt provides a cylindrical chamber 14. The latter opens out at its right end at the terminus 15 of the skirt 12 and there communicates with the inlet passage 11. The left opposite end of the skirt chamber 14 opens through to the outside of the housing. A plug 15 secured in proper manner to the housing covers this end of chamber 14. Valve 16 is adapted to seat at its 20 right inner end upon an annular shoulder 18 formed about an opening 19 through a vane 21 of the housing. Opening 19 communicates with a passage 22 that provides an outlet from the housing. When valve member 16 is moved leftward from its seat, opening 19 communicates 25 inlet passage 11 with the outlet passage 22. The outlet passage is connected in suitable manner as at 20 to the turbine intake end 6.

Cap 15 plugging the valve chamber has a boss 23 on its inner side extending a little way into the skirted chamber 14. The boss is of reduced diameter relative to the chamber and provides a clearance 24 around it, in which clearance sleeve valve 16 is adapted to slide when unseated. Fastened by bolts 17 to the underside of boss 23 is a circular plate 25. About the periphery of plate 25 30 is a lip 26 contacting the inner wall of sleeve valve 16. Over this lip the sleeve valve is adapted to ride. Axially extending from plate 25 is a tubular extension 27. Extension 27 opens out through the center of plate 25 at its left end, and it is closed over at its opposite free end by 35 a reduced threaded extension 28. A disc plate 29 is axially retained between a shoulder 31 and a nut threaded onto extension 28. Disc plate 29 has a peripheral lip 32 over which the lower portion of sleeve valve 16 is adapted to ride. The space between plate 25 and plate 40 29 is divided off into compartments 33, 34 by a circular vane 35 which is integral with the interior wall of sleeve 45 16. Tubular member 27 extends closely through a hole axially of vane 35.

Threaded into the covering plug 15 is a pair of fittings 50 36 and 37. Fitting 36 has a passage through it which communicates, by way of a recess 30 in the underside of boss 23, with the tubular element 27. The latter communicates with compartment 34 through a plurality of radial ports 10. Fitting 37 has a passage through it 55 which communicates through plug 15 and plate 25 with compartment 33. By this arrangement pressure air fed through fitting 36 to compartment 34 acts against the vane 35 to slide valve 16 leftward from its seat, whereupon pressure air flows from the inlet passage 11 to the outlet passage 22 to attack and rotate the turbine 1. On 60 the other hand, pressure air fed through fitting 37 enters compartment 33 and acts against the opposite side of vane 35 to slide valve 16 toward its seat so as to restrict the flow of pressure air to the turbine.

By this arrangement, it is clear that by controlling the flow of pressure air through the fittings 36 and 37 the flow of pressure air attacking the turbine may be regulated and, as a consequence, the speed of the turbine controlled.

70 A third fitting 38 laterally through the valve housing provides a passage communicating with the inlet passage 11. This fitting is connected by a line 40 to a fitting 39

of the governor device 3. This device acts to control the flow of pressure air through fittings 36 and 37.

The governor mechanism is supported in the interior of a housing 42. The interior of the housing provides an elongated cylindrical chamber 43 in axial communication with a larger bodied chamber 44. Chamber 43 has an annular recess 45 in its wall, which communicates by fitting 39 and line 40 with valve fitting 38. A second recess 46, parallel with the latter and spaced to the right of it, communicates by a fitting 41 and a line 47 with valve fitting 37. A third recess 48 parallel with recess 45 and spaced to the left communicates by a fitting 49 and a line 51 with valve fitting 36. The right end portion 52 of chamber 43 is suitably vented to the atmosphere; the large bodied chamber 44 is also suitably vented to the atmosphere.

A sliding spool member 53 carries a land 54 that is normally positioned between recesses 45 and 46, blocking communication of the one with the other. A second land 56 carried by spool 53 is positioned immediately to the left of recess 48, whereby the latter is normally blocked off from the vented chamber 44. By this arrangement recess 46 is normally blocked off from recess 45 and is in communication with the vented end of chamber 43. Recess 48 is normally blocked off from the vented chamber 44 and is in communication with recess 45. The space separating one recess from the other is equal to that of the thickness of either land. In this normal position of spool 53, pressure air entering inlet passage 11 flows through valve fitting 38, governor fitting 39, recesses 45 and 48, and governor fitting 49, to valve fitting 36 and compartment 34 to move the valve sleeve 16 from its seat. This allows pressure air flow through valve 2 to operate the turbine.

Through centrifugal means operated by the turbine when the latter exceeds a predetermined speed, spool 53 is caused to move its lands so as to restrict the flow of pressure air to the turbine. To this end, the main chamber 44 of the governor device 3 is closed over at its outer end by a block 56. In the latter, one end of a spindle shaft 57 is axially supported in a bearing 59 for rotatable movement. A gear 64 is mounted fast upon a projecting end of the spindle to drive the latter. Radially extending from shaft 57 within the large bodied chamber 44 is a cross member 65 providing a forked arm 66 on opposite sides of the shaft. Between each forked arm is pivoted a bellcrank 67. Arm 68 of the bellcrank is weighted; the other bellcrank arm 63 extends radially inward between the forked arm and is provided with a roller 69. A sleeve 71 slidably splined on shaft 57 has a flange portion 72 which limits against the forked arms 66 and over the rollers 69. The left end of spool 53 surrounds a thickened portion of sleeve 71 and is made fast thereto in suitable manner.

Surrounding shaft 57 is a coil spring 73 that limits upon a shoulder of sleeve 71 and is retained in a space between the sleeve and the inner wall of the spool 53. A second stub sleeve 70 is carried on the shaft within the hollow of the spool and is provided with a flange against the underside of which the opposite end of the coil spring 73 limits. The other end of shaft 57 is carried for rotatable movement in a bearing cup plate 75 that covers the outside end of chamber 43. An adjusting nut 76 threaded on shaft 57 abuts against the end wall of sleeve 70 and serves in adjusting the tensioning of the coil spring 73. Tension of the latter acts through sleeve 71 and the roller arms 69 to hold the weighted arms 68 parallel with spindle shaft 57. The latter is powered for rotation by the turbine through suitable gearing 50 that meshes with gear 64.

In the operation of the system, pressure air is supplied to the intake passage of valve member 2, from where it flows through fitting 38, recesses 45 and 48 of the governor, and then back to compartment 34 of valve 2 by way of fittings 49 and 36. This operates to unseat valve 16

and to allow pressure air flow to attack and rotate the turbine wheel. Rotation of the latter drives the governor spindle 57 through the gearing 50. As the speed of the turbine increases beyond a rated speed, the speed of the governor spindle 57 causes the fly weights 68 to pivot centrifugally outward. With this action, roller arms 63 slide sleeve 71 to the right along the spindle shaft, whereupon the lands of spool 53 are carried to cut off recess 45 from 48, and to unblock recess 46 for communication with recess 45. With this action air pressure flow through fitting 38 is diverted to recess 46 and ultimately through fitting 37 to compartment 33 of valve 2, whereupon valve member 16 is moved toward closed position and cuts down air flow to the turbine. In this action the air in the opposite compartment 34 cushions the movement of the valve and vents by way of fitting 36 to the vented chamber 44. When valve member 16 is moved to open position, air in the other compartment 33 acts as a cushion as the air vents through fitting 37 and chamber 43 to atmosphere.

By this arrangement it can be seen how rotation of the turbine below or above a certain set speed would cause the valve sleeve 16 to oscillate back and forth so as to hold the turbine shaft to a governed desired speed. The speed of the governor spindle, at which the bellcranks 66 start to pivot under action of the rotating spindle, may be regulated by adjusting the tension of the coil spring by means of nut 76.

The invention finds particular use where the turbine is employed in powering the actuator of an aileron unit in aircraft. In such a unit the turbine is continuously driven by pressure air supplied from the bleed air of a compressor unit of the craft, and, when required, is engaged through suitable means to drive the aileron unit. When the load of the actuator is applied to the turbine, the latter necessarily slows up; when the load is released, the latter operates at increased speed. Through use of the invention, the turbine speed is held at constant rate. This constant speed rate is continued without appreciable time lag when the turbine is loaded and unloaded. Loading of the turbine will slow the turbine down, but this is only momentary, the governor acting quickly to control the air feed to the valve to increase the flow therethrough until the turbine again reaches its constant speed rate. Similarly, where the load is freed from the turbine, the latter suddenly increases its speed, but only momentarily, for the governor and valve respond quickly to restrict the pressure flow through the valve and slow the turbine down again to its rated speed.

Although but one embodiment of the invention has been illustrated and described in detail, it is to be expressly understood that the invention is not limited thereto. Various changes can be made in the design and arrangement of the parts without departing from the spirit and scope of the invention as the same will now be understood by those skilled in the art. And it is my intent, therefore, to claim the invention not only in the form as shown and described, but also in all such forms and modifications as may reasonably be construed to be within the spirit of the invention and the scope of the appended claim.

I claim:

A main valve comprised of a housing including an inlet passage, an outlet passage and a vane wall having a circular opening which connects said passages; an annular recess in the vane wall around said opening providing a valve seat; said housing having a circular skirt wall extending into said inlet passage toward said valve seat and providing a valve chamber; a plug member cooperating with the housing and exteriorly closing off said valve chamber; said plug member having a circular boss extending into said valve chamber in spaced relation thereto; a circular plate mounted on the face of said boss and having a tubular extension projecting inwardly; the inner end of said extension being closed and having

a disc plate mounted thereon facing said circular plate; said disc plate being spaced from said valve seat and having its peripheral edge adjacent the end of said skirt wall; a sleeve valve sleeving said circular boss, said circular plate and said disc plate and contacting said valve seat; said sleeve valve having a partition wall across the interior of said sleeve valve to said extension and forming with said disc plate a first compartment and with said circular plate a second compartment; said sleeve valve being slidable in said valve chamber from said valve seat and over said plug boss to provide a flow path to said circular opening; said tubular extension having radial holes communicating said first compartment with the interior of said tubular extension; first passage means in said plug member connected to the interior of said tubular extension; second passage means in said plug

member and said circular plate opening into said second compartment whereby pressure air supplied to said first compartment can slide said sleeve valve from said valve seat and over said boss and whereby pressure air supplied to said second compartment will reseat said sleeve valve.
